UNITED STATES PATENT OFFICE.

HANS HANSON, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,279,687.

Specification of Letters Patent. Patented Sept. 24, 1918.

Application filed February 12, 1912. Serial No. 677,052.

To all whom it may concern:

Be it known that I, HANS HANSON, a citizen of the United States, residing in Hartford, in the county of Hartford and State of Connecticut, have invented certain new and useful Improvements in Combined Type-Writing and Computing Machines, of which the following is a specification.

This invention relates to computing machines of the kind in which pins or devices are set by means of numeral keys and are then caused to coöperate with dial wheels to determine the extent of rotation of the latter.

15 One of the principal objects of the invention is to enable a single set of such key-set pins or devices to coöperate with any of a series of sets of dial wheels.

The invention is illustrated in connection with a combined typewriting and computing machine of the Underwood-Hanson type, in which the key-set pins are carried upon rack bars, these rack bars having teeth which mesh with pinions to turn the dial wheels.

25 In carrying out my improvements, I substitute for the dial wheels a set of master wheels, and I arrange a series of sets of dial wheels upon a carriage; so that by moving the carriage, any desired set of dial wheels can be brought into conjunction with the single master set. The paper carriage of the type-writing machine is provided with a series of dogs, one for each of the sets of dial wheels, and these dogs, one after another, 35 operate the denomination devices which select the pin bars or racks which are to coöperate with the keys. Hence, during a single run of the paper carriage, all of the dial wheel sets can be operated one after another by the same set of master wheels.

40 Other objects and advantages will herein-after appear.

In the accompanying drawings,

Figure 1 is a sectional side elevation of 45 a combined typewriting and computing machine embodying the present improvements.

Fig. 2 is a plan of the dogs on the paper carriage of the typewriter and the denomination jacks operated thereby.

50 Fig. 3 is a sectional elevation similar to a portion of Fig. 1 but on a larger scale.

Fig. 4 is a view similar to Fig. 3, but show-

ing one of the sets of dial wheels meshing with the set of master wheels.

Fig. 4^a is a plan of one train of dial wheel, 55 master wheel and tens carrying mechanism, the parts in normal positions.

Fig. 4^b is a detail section showing the one-way clutch connection whereby the carry-over assisting shaft is driven solely during 60 the return movement of the general operator.

Fig. 5 illustrates the normal position of the feeding dog of the carriage which carries the dial wheels; and Fig. 6 illustrates the abnormal position thereof.

Fig. 7 is a general plan of the computing mechanism in the base of the machine.

Numeral keys 1 of the typewriter depress levers 2 to vibrate bell cranks 3, to swing type bars 4 up to print against a platen 5, 70 which is mounted on a carriage 6. The latter is driven by a spring-barrel 7, and has a rack 8 meshing with a pinion 9, connected to escapement wheel 10, which is controlled by dogs 11; said dogs operated by a universal 75 bar 12, which is driven by heels 13 on the type bars.

Said keys 1 have stems 14 to depress arms 15 on rock shafts 16, forming parts of linkages 17, which are depressed by said keys to 80 engage and depress computing pins 18, the latter suitably mounted on bars 19. These bars 19 are elevated one at a time, through the instrumentality of one of the dogs 20 on the carriage 6, said dog engaging jacks 21 one after another, to depress links 22 and vibrate levers 23, which engage linkages 24, to raise the rear ends of said bars 19 *seriatim*. As stated above, there is one of the dogs 20 for each column in which computing is done. 90

After the keys 1 have been depressed to print the desired number on the work sheet, the operative pulls forwardly a handle 25, which is provided upon a rock shaft 26, the latter extending across the machine, and having at its ends segments 27, which mesh with idle pinions 28, meshing with opposite racks 29, which form parts of the general operator; said racks connected by cross bars 30, 31.

The forward movement of said handle 25 carries the general operator forward, and cross-bar 30 engages such pins 18 as have been depressed by the keys, and drives forward the bars 19 accordingly; said bars hav-

ing on their forward ends racks 32 to mesh with pinions 33, which are connected to computing wheels 34; the latter loosely mounted on an arbor 35.

5 These computing wheels 34 serve as a set of master wheels whereby may be operated any of a series of sets of dial wheels 36, said dial wheels being mounted upon a carriage 37, whereby the sets may be presented one at 10 a time to the master set of computing wheels. The dial wheels have ten peripheral teeth 38, which may mesh with the teeth of the master wheels 34; and upon the several teeth 38 are provided numerals to be read 15 for the usual purpose. The carriage may be a box-like structure, as illustrated, and may have a front roll 39 to run on a rail 40 and rear rolls 41 to run on a rail 42. The rail 42 may be rounded, and the rolls 20 41 may be made concave so that there may be a pivotal or hinge action, to permit the carriage to rock from the Fig. 3 position, in which the dial wheels 36 are out of mesh, to the Fig. 4 position, in which one of the sets 25 of dial wheels is in mesh with the master set 34. By this means, any rotation of the master wheels 34, which is effected by the racks 32, is transmitted to the dial wheels 36 which are in mesh therewith, the dial wheels 30 of the other sets not being affected.

The keys 1 having been operated to print the numerals upon the work sheet, and the carriage 37 having been adjusted along its tracks to bring a set of dial wheels opposite the master set 34, the general operator handle 25 is pulled, and the carriage 37 is swung to bring the dial wheels into mesh with the master wheels before the latter begin to turn; there being some lost motion 40 of the general operator 29 before the pin-operating bar 30 engages the first depressed pin 18. This backward swinging or shifting movement of the carriage 37 is effected by a lever 43, pivoted at 44 upon the framework 45 and carrying at its forward end a roll 45, which bears down upon a bar or plate 46 upon the carriage, to depress the rear portion thereof and swing the dial wheels backwardly. The lever is operated by means of 50 a cam disk 47 which rotates in opposite directions during the forward and backward movements of the general operator, being for this purpose provided with a gear 48, which is connected by an idle gear 49 to one 55 of the racks 29 of the general operator.

The cam disk has in its edge a depression 50 in which normally rests a roll 51 provided upon the rear end of said carriage swinging member 43. During the forward 60 stroke of the general operator, the roll 51 is forced out of the notch, thus vibrating the lever to swing back the dial wheel carriage. During the remainder of the stroke of the disk 47, said roll 51 rides upon its

periphery, thus holding the carriage 37 with 65 the selected set of dial wheels in mesh with the master wheel 34. The disk 47 need not make quite a full revolution, and the roll 51 need not, therefore, drop into the notch 50 at the completion of said forward stroke of the 70 general operator, but may remain upon the circular periphery of the disk 47 until the latter returns to normal position, thus holding the dial wheel set in mesh with the master set during the tens-carrying operation 75 which occurs during the return stroke of the general operator.

It will be understood that at the completion of the return stroke of the general operator and of the disk 47, the roll 51 will 80 drop again into the notch 50, thus permitting the carriage 37 to swing by gravity to its forward or normal position.

Upon each of the dial wheels 36 is provided a starting tooth 52, forming part of 85 a tens-carrying or carry-over mechanism; and when the dial wheels are in the Fig. 4 position, any starting tooth 52 may effect an operation of a tens-carrying train, the principal members of which comprise a 90 nine-toothed pinion 53 and a three-toothed pinion 54 fixed to pinion 53. The tooth 52 operates the pinion 53 by means of an intervening idle pinion 55. These idle pinions are mounted loosely upon a fixed arbor 56; and the pairs of pinions 53, 54 are mounted loosely upon a fixed arbor 57. The three-toothed pinion 54 is in position to operate the master wheel 34 of next higher denomination, but is normally out of mesh therewith, as will be understood at Fig. 3. The starting tooth 52 turns the double pinion 53, 54 in the direction of the arrow from the Fig. 3 position to the Fig. 4 position, and thus brings the pinion 53 into position to be engaged by its associated driving spur 58, which operates during the return stroke of the general operator 29. Every third tooth on the pinion 53 is cut away, as at 59, to make a clearance for the associated spur 58, so that the spur cannot turn the tens carrying train unless the latter has been first started by the tooth 52.

Thus it will be seen that the dial wheels 36 are provided with teeth 52 for starting 115 their respective tens-carrying trains; each tooth 52, once in each revolution of its wheel, engaging one of the teeth on the pinion 55, for this purpose. This is done while the dial wheel 36 is moving from "9" to "0", 120 the pinion 53 turning one-ninth of a revolution from the Fig. 3 position to the Fig. 4 position; while the operation of the tens-carrying train is completed, during the return stroke of the general operator, by one 125 spur 58 of a set which is fixed upon a transverse shaft 60, which is driven from the rack 29 through idle gear 49, an idle pinion

61, and an idle pinion 62, the last-mentioned pinion meshing with a pinion 63 on said shaft 60.

The pinion 63 has a clutch connection 5 with said shaft 60, so as to revolve idly during the forward stroke of the general operator 29, and to make a complete revolution during the return stroke thereof. The clutch connection comprises a ball 64 fitted 10 in a pocket 65 in the shaft, and pressed by a spring 66 into a recess 67 in pinion 63; the ball connecting the pinion and shaft during the return stroke of the pinion, but releasing the shaft during the initial stroke 15 of the pinion.

The spurs 58 are placed in helical order along the shaft 60, so as to operate the carry-over trains *seriatim*. So long as any carry-over train remains in normal position, as at 20 Fig. 3, the shaft 60 may revolve idly with respect thereto; but when a train is started from the Fig. 3 position to the Fig. 4 position, one of the uncut teeth of the pinion 53 moves into the path of its spur 58, and 25 the latter therefore, at the ensuing rotation of the shaft 60, drives the tens-carrying train and advances the next higher master wheel 34 and hence the dial 36 with which the latter meshes, the shaft 60 thereafter 30 completing its revolution to normal position, being held in normal position by a spring detent, not shown herein but disclosed in United States Patent No. 816,819, granted to me March 27, 1906, and in the 35 pending application of F. A. Hart, No. 466,836, filed December 8, 1910.

It will be noticed that the pinion 33, in each instance, is connected to its computation wheel 34 by means of a ratchet 68 40 and a pawl 69, to permit the computation wheel to be advanced by the tens-carrying train independently of its rack 32.

The master wheels and the dial wheels are all driven by both the racks 32 and the 45 spurs 58, while the carriage 37 is in its Fig. 4 position; and at the conclusion of such operation, the carriage may return to its normal Fig. 3 position, thus disconnecting the dial wheels from the master wheels. The 50 latter may have spring detents 70, and each set of dial wheels may have a single detent bar 71 pivoted at 72 to the carriage and pressed by a spring 73 into engagement with all of the dial wheels in the set. When the 55 carriage is being swung back from Fig. 3 to Fig. 4, an arm 74 on said detent bar is intercepted by a trip 75, and all the dial wheels in the set move out of engagement with said bar detent 71 as they move into 60 mesh with the master wheel 34; there being preferably no point in which control of the dial wheels is lost.

The feeding movement of the dial wheel carriage 37 is effected by a spring 76 which

is connected by a cord 77 to a pin 78 on 65 the carriage 37, and tends always to draw the carriage to the left at Fig. 7. Upon the carriage is a rack comprising a series of teeth 79, one for each computing head 36, of which there may be as many as desired 70 upon said carriage; the latter may of course be of any desired length, in order to accommodate any required number of computing heads.

A dog 80 is normally in engagement with 75 the teeth of rack 79 and restrains the same against being propelled by said spring 76. When, however, the carriage is swung to the Fig. 4 position, the rack is swung down out of engagement with said pawl or dog 80 and 80 into engagement with a fixed dog or detent 81, so that the latter temporarily restrains the carriage from traveling. While the rack 79 is so depressed, a spring 82 snaps the dog 80, which is pivoted at 83 upon the framework, from a normal position at Fig. 5 past the tooth 79 from which it has just escaped. The position at Fig. 6 corresponds with that 85 at Fig. 4. Upon the return of the carriage 37 to normal forward position, Fig. 3, the rack 79 escapes from the detent 81 and rises to permit its succeeding tooth 79 to engage the feeding dog 80, as at Figs. 3 and 5; the carriage 37 of course making a jump equal to the distance between the teeth 79, which 90 is equal to the spacing of the dial wheel heads 36 at Fig. 7. After a line of writing is completed and the paper carriage 6 of the typewriter has been returned to begin 95 a new line of writing, the carriage 37 may 100 be returned by hand to bring the first or any desired adding head thereon into position for coöoperating with the master wheel set 34.

Variations may be resorted to within the 105 scope of the invention, and portions of the improvements may be used without others.

Having thus described my invention, I 110 claim:

1. In a computing machine, the combination 115 with a series of actuating racks, of a master set of wheels driven thereby in one direction, a plurality of sets of dial wheels, said dial sets adjustable in one direction to bring any selected set of dial wheels to said master set, and also movable in another direction to bring the selected set of dial wheels into mesh with said master set to be driven thereby, and carry-over gears meshing with said master set of wheels. 120

2. The combination of a single master set 125 of computing members, means for operating them concurrently including a general operator, a carriage, a series of sets of dial wheels on said carriage, said carriage sets engageable one at a time with said master set to be operated thereby, and means dependent upon the actuation of said general

operator for feeding the carriage to bring the sets successively into position for coöperation with said master set.

3. In a computing machine, the combination with a series of actuating racks, of a master set of wheels driven thereby, a plurality of sets of dial wheels, any set of which may be controlled by said master set of wheels, a general operator, means controlled thereby for driving said master set of wheels and the coöperating set of dial wheels on one stroke of said general operator, carrying mechanism, means for initiating a carrying operation by the wheels of any active set of dial wheels, and means for completing the carrying-over operation on the active set of dial wheels on the return stroke of the general operator.

4. The combination of a master set of computing wheels, means for operating them concurrently, including a general operator, a carriage, a series of sets of dial wheels on said carriage, said carriage sets engageable one at a time with said master set to be operated thereby, means connected to said general operator for feeding the carriage to bring the sets successively into position for coöperation with said master set; said series of sets being mounted on said carriage out of position for meshing with said master set, and means also dependent upon said general operator for moving said carriage sets into mesh with said master set.

5. The combination with a master set of computing members, of means for operating them concurrently, a carriage, a pair of separate tracks on which said carriage normally runs, and a series of sets of wheels mounted on said carriage out of mesh with said master set of members, said carriage being tilttable or shifttable about one of said tracks as a fulcrum and away from the other track to bring any of its sets into mesh with said master set to be operated thereby.

45 6. The combination with a master set of computing devices, of means for operating them concurrently, a carriage, a series of sets of computing wheels mounted on said carriage out of mesh with said master devices, said carriage being tilttable or shifttable to bring any of its sets into mesh with said master set to be operated thereby, and means for feeding the carriage; said operating means including a general operator, and means controlled by said general operator for shifting said carriage to bring any of its sets into mesh with said master set.

7. The combination with a master set of computing wheels, of means for operating them concurrently including a general operator, a carriage, a series of sets of dial wheels mounted on said carriage out of mesh with said master set of wheels, said carriage being tilttable or shifttable by said general oper-

ator to bring any of its sets into mesh with 65 said master set to be operated thereby, and an escapement mechanism including a part on the framework and a second part on the carriage to shift with the latter relatively to the first part at the operation of the 70 general operator.

8. The combination with a master set of computing members, of means including a general operator for operating said members concurrently, a carriage, two tracks on 75 which the carriage normally runs, a series of sets of computing wheels mounted on said carriage and normally out of mesh with said master set of members, a rotary cam connected to said general operator, and means 80 controlled by said cam for tilting or shifting said carriage about one of its tracks as a fulcrum, to bring a set of wheels thereon into mesh with said master set.

9. The combination with a master set of computing members, of means including a general operator for operating said members concurrently, a carriage, a series of sets of computing wheels mounted on said carriage and normally out of mesh with said master 90 set of members, means controlled by said general operator for shifting said carriage to bring a set of wheels thereon into mesh with said master set, a driving spring for said carriage, and an escapement mechanism 95 including coöperating parts, one of which is mounted on said carriage to be effectively operated thereby at the wheel-shifting movement of the latter.

10. The combination of a master set of 100 computing wheels, a general operator for operating said wheels concurrently, a carriage, a series of sets of computing wheels on said carriage, said carriage sets engageable one at a time with said master set to be 105 operated thereby, and a set of tens-carrying or transfer trains dependent upon the carriage wheels but mounted upon the framework of the machine to coöperate with said carriage sets through said master set one 110 after another.

11. The combination of a master set of computing wheels, a general operator for operating said wheels concurrently, a carriage, a series of sets of computing wheels 115 on said carriage, said carriage sets engageable one at a time with said master set to be operated thereby, a set of tens-carrying or transfer trains dependent upon the carriage wheels but mounted upon the framework of the machine to coöperate with said carriage sets one after another through said master set; said carriage sets being normally out of position for coöperating with said master set and said tens-carrying trains, and means for moving said carriage sets into engagement with said master set and said tens-carrying trains. 120 125

12. The combination of a master set of computing wheels, a master set of tens-carrying or transfer trains operating through said master set of computing wheels, a general operator for said sets, a carriage, and a series of sets of computing wheels on said carriage, said carriage sets engageable one at a time with both of said master sets to be operated concomitantly thereby; the wheels on said carriage having devices to initiate the tens-carrying operations.

13. The combination of a relatively stationary master set of computing wheels, a relatively stationary master set of tens-carrying or transfer trains, a general operator for said sets, a carriage, and a series of sets of computing wheels on said carriage, said carriage sets engageable one at a time with said master sets to be operated concomitantly thereby; each of said tens-carrying trains comprising a pinion, each wheel in each of said carriage sets having a tooth for starting said pinion, and each of said tens-carrying trains also comprising a second pinion in mesh with the first and having a third pinion to engage the computing wheel of next higher order in said master set; said general operator including means for engaging said tens-carrying trains to drive the same.

14. In a combined typewriting and computing machine, the combination with a letter-feeding carriage, of a master set of computing wheels, several complete sets of readable dial wheels all normally out of engagement with said master set, said sets adjustable in one direction independently of said letter-feeding carriage, to bring any selected set of dial wheels to said master set, and also movable in another direction to bring the selected set of dial wheels into mesh or coöperation with said master set, and means, including a set of numeral keys and denomination-selecting devices, to coöperate with said letter-feeding carriage for controlling the operation of said master set upon said dial sets successively, during a single run of the letter-feeding carriage.

15. The combination with a master set of computing wheels, of a carriage, sets of readable dial wheels upon said carriage, said dial wheels normally out of engagement with said master set, said carriage movable in one direction to bring any selected set of dial wheels to said master set, and movable in another direction to bring the selected set of dial wheels into mesh or coöperation with said master set, a letter-feeding carriage, and means to coöperate therewith for controlling the operation of said master set once for each of said sets of dial wheels during a single run of said letter-feeding carriage.

16. The combination of a master set of computing devices, means for operating them concurrently, a carriage, a series of sets

of computing wheels on said carriage, said carriage sets engageable one at a time with said master set to be operated thereby, devices for feeding the carriage to bring the sets successively into position for coöperation with said master set; said series of sets being mounted on said carriage out of position for meshing with said master set; and means for moving said carriage sets into and out of mesh with said master set and concomitantly effecting an operation of said feeding devices.

17. The combination of a master set of computing devices, a general operator having means for operating them concurrently, a carriage, a series of sets of computing wheels on said carriage, said carriage sets engageable one at a time with said master set to be operated thereby, means controlled by said general operator for feeding the carriage to bring the sets successively into position for coöperation with said master set; said series of sets being mounted on said carriage out of position for meshing with said master set; and means connected to said general operator for moving any of said carriage sets into mesh with said master set and holding it there.

18. The combination with a master set of computing members, of means for operating them concurrently, a carriage, a hinge-rail or track therefor, a series of sets of computing wheels mounted on said carriage out of mesh with said master members, said carriage being tilttable on said track to bring any of its sets into mesh with said master set to be operated thereby, means to tilt the carriage, and means connected to said tilting means for feeding the carriage.

19. The combination of a relatively stationary master set of computing wheels, a general operator for operating said wheels concurrently, a carriage, a series of sets of computing wheels on said carriage, said carriage sets engageable one at a time with said master set to be operated thereby, a relatively stationary set of tens-carrying or transfer trains to engage and drive wheels in said master set and mounted upon the framework of the machine to coöperate with said carriage sets one after another; said carriage sets having means for initiating the tens-carrying operations and being normally out of position for coöperating with said master set and said tens-carrying trains, means for moving said carriage sets into engagement with said master set to be driven thereby and also with said tens-carrying trains, to initiate the movements of the latter; said general operator having means to drive the tens-carrying trains that have been started by the wheels in any carriage set, each tens-carrying train comprising a partly mutilated power-driven pinion, a second pin-

ion to engage the master wheel of next higher denomination, and a third pinion in mesh with the first and in position to be engaged by the starting tooth of the momentarily associated carriage computing wheel.

20. The combination with a relatively-stationary master set of members, of a carriage, wheels on said carriage operable by said master set, but normally out of engagement therewith, a feeding mechanism for said carriage acting to bring said carriage wheels into position for coöperation with said master set, and shifting or tilting means for said carriage acting both to operate the feeding mechanism and to bring the carriage wheels into actual engagement with said master set of members.

21. In a computing machine, the combination with a series of actuating racks, of a master set of wheels driven thereby in one direction, a plurality of sets of dial wheels, said dial sets adjustable in one direction to bring any selected set of dial wheels to said master set, and also movable in another direction to bring the selected set of dial wheels into mesh with said master set to be driven thereby, and carry-over devices associated with said master set of wheels and operating the dial wheels through said master set.

22. The combination with a plurality of sets of computing wheels, of a computing mechanism for determining the extent of rotation of said computing wheels, actuating mechanism for said sets, means for effecting a relative movement between said sets and said actuating mechanism to bring about individual juxtaposition between each of said sets and said actuating mechanism, shifting means for affording relative to-and-from movement between each set and said actuating mechanism, to bring about an actual coöperation, so that said actuating mechanism can rotate the computing wheels of the set in juxtaposition thereto, and means to enable one of said relative movements to control the other of said relative movements.

23. The combination with a plurality of sets of computing wheels, of actuating mechanism for said sets, a general operator for said actuating mechanism, means for effecting a relative movement between said sets and said actuating mechanism, to bring about individual juxtaposition between each of said sets and said actuating mechanism, shifting means for affording relative to-and-from movement between each set and said actuating mechanism, to bring about an actual coöperation, so that said actuating mechanism can rotate the computing wheels of the set in juxtaposition thereto, means to enable one of said relative movements to control the other of said relative movements, and controlling means actuated from said

general operator for governing both of said relative movements.

24. The combination with a set of computing wheels, of a traveling carriage for said set, a rail and roller support for said carriage, and actuating mechanism for said set, said carriage being traversable along said rail to bring said set into the sphere of operation of said actuating mechanism, and also being pivotal about said rail to bring said set into actual coöperation with said actuating mechanism.

25. In a combined typewriting and computing machine, the combination with numeral keys, of a series of computing heads for computing in various columns, a single set of devices in which numbers are temporarily set up before being carried into said heads, a general operator for actuating said devices to carry the set up numbers into a head, and means operated by said general operator for bringing the next head to effective position with reference to said devices when the number has been completely carried into one head.

26. In a combined typewriting and computing machine, the combination with numeral keys, of a series of computing heads for computing in various columns, each computing head including a series of computing wheels, a single set of devices in which numbers are temporarily set up before being carried into said heads, a general operator for actuating said devices to carry the set up numbers into a head, means operated by said general operator for bringing the next head to effective position with reference to said devices when the number has been completely carried into one head, actuating devices driven by the first-named devices and arranged in turn to drive said computing wheels to an extent determined by the numbers set up, and carry-over devices effective on said heads through said actuating devices.

27. In a combined typewriting and computing machine, the combination with numeral keys, of a computing carriage comprising a series of computing heads, a single master head for actuating any one of said computing heads, each of said heads comprising a set of computing wheels, locking means normally holding the wheels locked in each head, a general operator for carrying numbers through said master head into the computing head which is effective at the moment, means moved by said general operator for first freeing said effective computing head from its locking means and then bringing its wheels into mesh with the master head, and carry-over devices effective on the said computing head through the master head.

28. In a combined typewriting and com-

- puting machine, the combination with numeral keys, of a computing carriage comprising a series of computing heads, a single master head for actuating any one of said computing heads, each of said heads comprising a set of computing wheels, locking means normally holding the wheels locked in each head, a general operator for carrying numbers through said master head into the computing head which is effective at the moment, means moved by said general operator for first freeing said effective computing head from its locking means and then bringing its wheels into mesh with the master head, carry-over devices effective on the said computing head through the master head, and means operated by said general operator to bring the next head into effective position at the end of each operation.
29. In a computing machine, the combination with a dial wheel, of an actuating wheel therefor, said dial wheel having carry-over mechanism comprising a driving wheel effective on the actuating wheel, normally ineffective means by which said driving wheel
- 5 may be driven, and a wheel constantly in mesh with said driving wheel and adapted to be moved by said carry-over tooth to move the driving wheel to effective position where it will be driven. 85
30. In a computing machine, the combination with a dial wheel, of an actuating wheel therefor with which it is normally out of mesh, said dial wheel having a carry-over tooth, carry-over mechanism comprising a 85 driving wheel effective on the actuating wheel, normally ineffective means by which said driving wheel may be driven, and a wheel normally in ineffective position but effective when the actuating wheel is effective on the dial wheel, and constantly in mesh with said driving wheel and adapted to be moved by said carry-over tooth to move the driving wheel to effective position where it will be driven. 40

HANS HANSON.
